United States Patent Office.

WILLIAM RICHARD, OF CLYDE, OHIO.

Letters Patent No. 92,100, dated June 29, 1869.

IMPROVEMENT IN PRUNING-KNIFE.

The Schedule referred to in these Letters Patent and making part of the same.

To all whom it may concern:

Be it known that I, WILLIAM RICHARD, of Clyde, in the county of Sandusky, and State of Ohio, have invented certain new and useful Improvements in Pruning-Knives; and I do hereby declare that the following is a full, clear, and exact description thereof, reference being had to the accompanying drawings, and to the letters of reference marked thereon, which form a part of this specification, in which is represented a plan view of my pruning-knife.

My invention consists in connecting the shanks of a pruning-knife with a bar or link, constructed substantially is the manner hereinafter set forth.

To enable others skilled in the art to which my invention appertains, to make and use the same, I will now describe its construction and operation.

In the accompanying drawings—

A A' represent two metal bars, provided at their lower ends with handles, B B, and at their upper ends with curved knives, as seen at a a.

It will be seen that the curve on A is sharpened on its outer surface, while the curve on A' is sharpened on its inner surface, the object of which will be herein-after fully described.

The bar A' is formed with a slot, b, near the curve a. Through this slot is passed the rivet c, which is secured to bar A.

D is a metal bar, formed at one end with a knife, as seen at d.

This bar is pivoted at its upper end to the bar A, and its lower end to the bar A'.

By this arrangement the bar A' is made to have a downward cut.

I do not, however, claim this feature as new, as the same thing has been done before.

Having thus described my invention,

What I claim as new, and desire to secure by Letters Patent, is—

The link D, formed at its upper end with a knife or hook, d, in combination with the shank A, and arranged to operate as and for the purpose set forth.

In testimony that I claim the foregoing as my own, I affix my signature, in presence of two witnesses.

WILLIAM RICHARD.
